PREFABRICATED BUILDING

Howard T. Patterson, Woonsocket, R. I., assignor
to Austin T. Levy, Harrisville, R. I.

Application May 27, 1938, Serial No. 210,471

11 Claims. (Cl. 72—16)

My invention relates to prefabricated buildings.

It has heretofore been proposed to make the outer walls of such buildings of panels of insulating board mounted in marginal metallic frames and carrying reenforcing and anchoring material spacing rods, with a continuous sheet of wire mesh extending over the rods and the studs of the metallic frame, and cementitious material clinched by the wire mesh. However, it has been found that cracks sometimes appear in the cementitious material between the studs, particularly in walls of considerable length, and that these cracks, being irregular and extending clear through the stucco, mar the appearance of the house and are difficult to fill successfully.

My invention has among its objects to provide an improved construction whereby such cracking is minimized. A further object of my invention is to provide an improved expansion joint whereby it is made possible through controlling the effects of expansion and contraction of the wall, to minimize the difficulties heretofore experienced. A still further object of my invention is to provide an improved construction wherein the wire mesh is associated in an improved manner with improved reenforcing means and an expansion joint of improved construction, all whereby it is made possible to produce an improved wall. These and other objects and advantages of my improvements will, however, hereinafter more fully appear.

In the accompanying drawing I have shown for purposes of illustration, one embodiment which my invention may assume in practice.

In the drawing:

Figure 1 is a side elevation of a corner of a building equipped with my improved construction, portions of the wall being broken away to facilitate illustration;

Fig. 2 is an enlarged side elevation of a portion of an outside wall, all the cementitious material being removed and the wire mesh being shown over only a portion of the wall surface, in order to facilitate illustration, and

Fig. 3 is a transverse section on line 3—3 of Figure 2.

In this construction, the wall comprises a series of insulating boards or panels 1 disposed in a marginal metallic frame comprising a bottom channel sill 2, a top channel plate 3, and cooperating intermediate studs 4 and corner studs 5, each of the panels 1 carrying spaced reenforcing and anchoring material spacing rods 6 having wire mesh 7 disposed over the same and cementitious material, such as stucco 8, clinched

by the wire mesh; my improved construction herein being illustrated as applied to the panel 1 adjacent the corner stud 5.

In my improved construction, an improved expansion joint member 9 is provided substantially midway between adjacent rods 6 and longitudinally of these rods, the same extending from a point spaced slightly below the plate 3 to a point just above the sill 2. Herein, this member 9 is formed of a single sheet of sheet metal such, for example, as copper, tinned on its outer side. As shown, it is also provided with a middle, outwardly extending, preferably narrow and U-shaped, folded portion 10 of uniform cross section throughout most of its length and connected by a rounded tip at its outer end and spaced at its inner ends, and the latter are also herein integral with flat oppositely disposed strips 11 which extend along the full length of the opposite sides of the base of this portion 10. These strips 11 herein are each approximately as wide as the portion 10 is high, and provided with outwardly extending right angled flanges 12 on their outer edges. As shown, a rod 13, corresponding to the rods 6, is disposed inside each of these flanges 12.

In a preferred construction, the member 9 is suitably attached to the insulating panel 1 by means which also act to attach these rods and the wire mesh to the panel. Herein, shingle nails 14 are used with their heads 15 overlying the outer edges of the flanges 12 and opposite sides of the rods 13, two series of these nails 14 being provided, one on each side of each rod, with the nails disposed in staggered relation. In practice, it is found that such nails will firmly secure the rods 13 and expansion member 9 to the panel 1 without either extending clear through the panel board or being clinched on the opposite side thereof.

Here attention is further directed to the fact that the edges of different strips of wire mesh 7 are brought over the rods 13 and into adjacency to the portion 10 of the expansion member 9, while being spaced therefrom, this portion 10 thus being disposed in a vertically extending space or gap 16 between two sections of wire mesh 7. Further, the nails 14 connect the edges of these mesh strips to the panel 1 at each side of the expansion portion 10, while the wire is effectually spaced from the board 1 along each side of the portion 10, by the rods 13. Thus, it will be evident that any contraction or expansion of the wire portions on opposite sides of the gap 16 will cause a corresponding movement of the opposite walls of the portions 10.

Over the wire mesh when thus disposed, a coating of stucco or the like is applied. In practice, a first coating 17 is extended out to the rounded and closed extremity of the portion 10 on the expansion member 9, so that this tip is exposed when the coating is applied. Further, after coating 17 has dried, an outer, and thinner, coat 18 of stucco, such as a color coat, is applied, which coat overlies and conceals the extremity of the portion 10 while permitting some movement thereof.

In the use of my improved construction, it is made possible to control the forces acting to produce cracking in the stucco, in such manner as to minimize the tendency to crack; the expansion member connected, as described, to the rods and adjacent ends of the wire mesh, being free to expand or contract at its inner end where the maximum movement occurs and functioning effectively to permit a certain amount of expansion and contraction without cracking the outer coat. Further, it is evident that should this amount be exceeded, any crack which is formed, is produced along the portion 10, as distinguished from irregularly, and that this crack occurs only in the outer thin coat of stucco, as distinguished from extending through both coats of stucco.

As a result of my invention, I am able to minimize cracking and to control the same in such manner as substantially to improve the wall produced and markedly to improve the appearance of the same. Further, it will be evident that any cracking which occurs is slight and readily remedied, while my improvement also makes it possible, if desired, to locate the expansion joint in an inconspicuous position, such, for example, as under a conductor pipe leading downward along the same. Obviously, while I have herein shown only one such expansion joint, it will be evident that under different conditions, as many of these as desired may be provided in any suitable spaced relation in a wall or around the walls of a building. Attention is also directed to the fact that my improved construction is such that the expansion joint may be readily and quickly applied in any desired location after the wall has been assembled. Other advantages of my improved construction will be apparent to those skilled in the art.

While I have in this application specifically described one embodiment which my invention may assume in practice, it will be understood that the same is shown for purposes of illustration and that the invention may be modified and embodied in various other forms without departing from its spirit or the scope of the appended claims.

What I claim as new and desire to secure by Letters Patent is:

1. In a prefabricated building, a wall panel, adjacent sections of anchoring material expandable as a result of temperature changes, and having their edges terminating in adjacent spaced relation on one face of said panel and an expansion joint on said panel connected to the adjacent edges of said sections and in the space between adjacent edges thereof.

2. In a prefabricated building, a wall panel, adjacent sections of anchoring material thereon expandable as a result of temperature changes, said sections being secured to a face of said panel with their adjacent edges in spaced relation, an expansion joint on said panel bridging the space between said edges and connecting said sections and having an intermediate flexible portion disposed in the space between adjacent edges there-

of, and anchoring material spacing means fixed to said joint along opposite edges thereof adjacent the edges of said sections.

3. In a prefabricated building, a wall panel, adjacent sections of anchoring material thereon expandable as a result of temperature changes, said sections being secured to a face of said panel with their adjacent edges in spaced relation, and an expansion joint on said panel bridging the space between said sections and having spaced resiliently connected portions connected to different sections of anchoring material adjacent the spaced edges thereof.

4. In a prefabricated building, a wall panel, adjacent sections of anchoring material thereon expandable as a result of temperature changes, and an expansion joint on said panel connecting said sections, said expansion joint comprising a sheet metal member having a laterally expandable ribbed portion and laterally extending base portions fixed to said panel and to opposite sections of said anchoring material.

5. In a prefabricated building, a wall panel, adjacent sections of anchoring material thereon expandable as a result of temperature changes, and an expansion joint on said panel connecting said sections, said expansion joint comprising a sheet metal member having a laterally expandable ribbed portion and laterally extending base portions fixed to said panel and opposite sections of said anchoring material, and anchoring material spacing means overlying said base portions.

6. In a prefabricated building, a wall panel carrying anchoring material, cementitious material clinched by the latter, and an expansion joint between adjacent sections of said anchoring material, said expansion joint comprising a sheet metal member having a laterally expandable ribbed portion and laterally extending flanged base portions fixed to said panel and opposite sections of said anchoring material, and anchoring material spacing rods between the flanges of said flanged base portions.

7. In a prefabricated building, a wall panel, adjacent sections of anchoring material thereon expandable as a result of temperature changes, said sections being secured to a face of said panel with their adjacent edges in spaced relation, cementitious material clinched by the latter, and an expansion joint on said panel connecting said sections including a laterally expandable and contractible member connected to said sections and having a connecting portion projecting into between said spaced edges and said cementitious material.

8. In a prefabricated building, a wall panel, adjacent sections of anchoring material thereon expandable as a result of temperature changes, said sections being secured to a face of said panel with their adjacent edges in spaced relation, and an expansion joint on said panel connecting the adjacent edges of said sections, said expansion joint having anchoring material spacing rods along opposite edges of said joint spacing said material from said panel, and common means for connecting said joint, rods and anchoring material to said panel.

9. In a prefabricated wall, a panel, an expansion joint thereon having protruding spaced relatively movable portions and a rounded flexible portion connecting the outer extremity of said movable portions, anchoring material sections expandable as a result of temperature changes connected to said joint at opposite sides of said movable portions, a first coating of cementitious

material covering said anchoring material and having said rounded portion projecting there-through, and a second coating of cementitious material overlying said coating and said rounded end.

5 10. In combination, a panel board, spaced re-enforcing rods thereon, an expansion joint member disposed lengthwise between certain rods, and sections of anchoring material spaced by said rods and having adjacent edges connected to opposite sides of said member.

11. In combination, a panel board, spaced re-enforcing rods thereon, an expansion joint member disposed lengthwise between certain rods, sections of anchoring material spaced by said rods and having adjacent edges connected to opposite sides of said member, and cooperating spacing rods fixed to different sides of said member and to the edges of said anchoring material and between said member and the adjacent rods of said first mentioned rods.

5

10 HOWARD T. PATTERSON.

CERTIFICATE OF CORRECTION.

Patent No. 2,186,462.

January 9, 1940.

HOWARD T. PATTERSON.

It is hereby certified that error appears in the printed specification of the above numbered patent requiring correction as follows: Page 2, first column, line 63, claim 1, after the word "panel" insert a comma; and second column, line 54, claim 7, for "into between said spaced edges and" read between said spaced edges and into; and that the said Letters Patent should be read with this correction therein that the same may conform to the record of the case in the Patent Office.

Signed and sealed this 5th day of March, A. D. 1940.
